MULTIPLE STAGE CARBURETOR

Jorma O. Sarto, Walled Lake, Mich., assignor to Chrysler Corporation, Highland Park, Mich., a corporation of Delaware

Application December 8, 1953, Serial No. 396,982

38 Claims. (Cl. 123—127)

This invention relates to multiple stage liquid fuel carburetors for internal combustion engines and more particularly to a means for controlling the actuation of an auxiliary carburetor stage of a multiple stage carburetor in response to engine speed.

The characteristics of a conventional internal combustion engine equipped with a liquid fuel carburetor are such that the engine output torque will vary with a variation in engine speed. This variation in engine torque is caused by a number of factors, one of which is the change in the fuel mixing characteristics of the carburetor which accompanies a variation in engine speed design. As the engine speed increases, the intake air flow rate within the carburetor fuel mixing throat is also increased. When a single stage carburetor is used, the air flow rate which would produce the optimum fuel mixing characteristics in the single mixing throat thereof will normally occur throughout a low engine speed range. At a relatively higher engine speed range the mixing characteristics and air fuel ratio may deviate from the optimum and for this reason the engine output torque will normally tend to decrease with an increase in engine speed.

If a dual barrel carburetor is employed, and if both of the mixing throats are operative over the entire engine speed range, the air flow rate which would exist in each of the throats at low engine speeds would be such that the mixing characteristics would be relatively poor. On the other hand, the correct flow rate may exist at the higher engine speeds. Thus, the engine output torque will tend to increase with an increase in the engine speed throughout a substantial portion of the overall speed range below the output torque begins to fall off or decrease.

Accordingly, it has been found desirable to render the secondary stage of a dual carburetor installation inoperative at the lower engine speeds and to render the same operative at higher engine speeds. The dual carburetor unit will, therefore, function as a single stage carburetor over the lower engine speed range and the secondary stage thereof will function only at the higher engine speed range thus making it possible to take advantage of the resulting optimum mixing characteristics for both stages to obtain a maximum engine output torque over the entire speed range.

It is desirable to provide an automatic means for controlling the secondary stage to cause the same to be actuated at the proper engine speed. In order to avoid a sudden change in the magnitude of the output torque, it is necessary to actuate the secondary stage at an engine speed such that the engine output torque during engine operation with only the primary stage will be substantially the same as the engine output torque during operation with both carburetor stages.

In order that the control means for the secondary stage might be actuated at the proper engine speed, it is necessary to obtain an engine speed signal to initiate the automatic control response. In the present embodiment such a speed signal may consist of the engine coolant pump

discharge pressure which in turn is proportional to engine speed since the coolant pump is normally powered directly by the engine.

A primary object of the present invention is to provide a means which is responsive to engine speed for controlling the operation of the second stage of a two-stage carburetor so that the second stage will be inoperative at low engine speeds and operative at higher engine speeds.

A more specific object of the present invention is to provide a means which is responsive to engine coolant pump pressure to automatically control the second stage of a two-stage carburetor whereby the second stage thereof is rendered operative at speeds above a predetermined maximum value and at a predetermined range of throttle positions.

Another object of the present invention is to provide an automatic control for a multiple stage carburetor according to the preceding objects wherein a means is provided for connecting the throttle valves of the secondary stage with the throttle valves in the primary stage during movement of the primary throttle valve throughout a range of positions near the wide open throttle position. The primary throttle valve may in turn be actuated manually.

Another object of the present invention is to provide an automatic control for a multiple stage carburetor according to the preceding object wherein an engine speed responsive device associated with the automatic control is adapted to adjust the position of the secondary throttle valve actuating linkage at engine speeds above a predetermined value to permit the linkage to be contacted by a corresponding linkage for the primary throttle valve during movement of the primary throttle valve throughout a predetermined range of positions thereby providing for an adjustment of the fuel-air ratio over the throttle speed range of the secondary stage.

Another object of the present invention is to provide an automatic control means according to the preceding object wherein the speed responsive device comprises an engine coolant pump pressure responsive actuator and a "snap" type valve interposed in a fluid conduit between the pressure responsive actuator and the engine coolant pump, the said "snap" type valve being effective to cause the actuator to be positively and fully actuated substantially instantaneously when the pump pressure reaches a predetermined value.

Another object of the present invention is to provide an automatic control for a multiple stage carburetor which is responsive to engine speed and which comprises an engine speed responsive actuator positively connected to an auxiliary stage valve.

Another object of the present invention is to provide an automatic control as set forth in the preceding object wherein the engine speed signal for the speed responsive actuator is obtained from the engine coolant pump pressure and wherein a fluid conduit is provided between the actuator and the engine coolant pump. A fluid control valve is interposed in the conduit and actuated by means of the primary throttle assembly.

In general, the present invention as herein disclosed, comprises a carburetor having a pair of primary fuel mixing barrels and a pair of auxiliary barrels which are associated with the primary and secondary stages respectively. Each of the barrels is provided with a throttle valve for controlling the intake air flow rates therethrough. The throttle valves for the primary stage are mounted in tandem upon a common shaft and the throttle valves for the secondary stage are also mounted in tandem upon another common shaft. The primary throttle shaft is positively linked to a manually actuated foot throttle lever and another portion of the primary throttle shaft carries a lost motion element which is adapted to contact

a mating lost motion element pivotally carried by a lever which in turn is connected to the secondary throttle shaft.

A coolant pump pressure responsive actuator is mounted upon the carburetor and is linked to the pivoted lost motion element. Upon reaching a predetermined value the coolant pump pressure causes the actuator to move its associated lost motion element into a position in the path of movement of the other lost motion element as the primary throttle valve moves toward the wide open position. Therefore, the primary throttle valve linkage is adapted to control the opening of the secondary throttle during movement of the primary throttle valve throughout a predetermined operating range and when the speed of the engine exceeds a predetermined minimum value.

According to another embodiment of the invention a coolant pump pressure responsive actuator is provided on a four-barrel carburetor and the movable element of the actuator is positively linked to the secondary throttle shaft to actuate the same when the speed of the engine reaches a predetermined minimum. No direct mechanical connection is provided between the primary and secondary valves in this embodiment. However, the movement of the primary valve is effective to control the movement of a control valve which regulates the delivery of coolant pressure from the coolant pump to the actuator.

For the purpose of more particularly describing the present invention, reference will be made to the accompanying drawings in which:

Figure 1 is a top view of a four-barrel carburetor equipped with the second stage control of the present invention;

Figure 2 is a side view of the carburetor of Figure 1 showing a portion of the linkage associated with the primary and secondary stages;

Figure 3 is a bottom view of the carburetor of Figure 1;

Figure 4 is a side view of the carburetor of Figure 1 showing the side opposite from that shown in Figure 2;

Figures 5, 6, and 7 are perspective views of the throttle valves and the associated control levers. Each of the views shows the levers in relatively different positions for the purpose of more clearly illustrating the operation of the invention;

Figures 8 and 9 schematically show a modified arrangement of the control levers for the throttle valves. The coolant pump pressure responsive actuator is shown in the deenergized position in Figure 8 and in the energized position in Figure 9;

Figure 10 is a schematic showing of another embodiment of the present invention which is similar to the embodiment of Figures 1 through 7;

Figure 11 is a schematic representation of still another embodiment of the invention in which the coolant pump pressure responsive actuator is directly coupled to the secondary throttle shaft to actuate the same and in which the fluid conduit leading to the actuator includes a quick action flow control valve;

Figure 12 is an alternative form of a flow control valve which may be used with any of the presently disclosed embodiments; and

Figure 13 is another modified form of the invention having a flow control valve of a third form.

Referring first to the plan view of Figure 1, the construction is designated generally by numeral 10 and it includes four barrels which are separately identified by means of numerals 12, 14, 16, and 18. The four barrels are divided into pairs of two by a vertical transversely extending wall 70 which forms an integral part of the carburetor upper cast structure 22. The barrels 12 and 14 are grouped together on one side of wall 70 and the barrels 16 and 18 are grouped into separate pairs on the opposite side of wall 20. It will be seen from the following description that the pair of barrels 12 and 14 are associated with the primary stage and the pair of barrels 16 and 18 are associated with the secondary stage.

An automatic choke is shown generally at 24 and is

adapted to receive exhaust manifold air through the fitting 26. A shaft 28 extends from the choke device 24 through a suitable mounting portion 30 on the casting 22 into the space above the barrels 12 and 14 and is adapted to be rotatably adjusted by the choke device 24. A choke valve 32 is secured to the shaft 8 and is adapted to provide a choking action when the shaft 28 is rotated. The choke valve 32 is shown in the fully open position in Figure 1. The shaft 28 has an extension shown at 34 which carries linkage elements for causing shaft 28 to move a slight amount when the primary throttle valve reaches the wide open position.

The presently disclosed carburetor also includes metering jets and an accelerator pump boosting mechanism which are housed in a portion of the casting 22 shown at 36. Suitable linkage elements are provided for positively connecting the throttle linkage mechanism with a shaft 38 which is rotatably mounted in a portion 40 of the casting 22 and which is effective to control the elements within the casting portion 36.

A fuel inlet fitting is seen at 42 through which liquid fuel is admitted to a fuel bowl, not shown.

A venturi element is centrally disposed individually in each of the carburetor barrels and are designated by numerals 44, 46, 48, and 50. Each of the venturis has a fuel jet disposed therein, as seen at 52, 54, 56, and 58 respectively which are each adapted to discharge liquid fuel into the intake air stream which flows through the barrels during operation of the engine.

In the bottom view of Figure 3 the throttle valves are clearly shown disposed in the downdraft end of the barrels 12, 14, 16 and 18 and are separately designated by means of numerals 60, 62, 64, and 66, respectively. The downdraft portions of the four barrels are formed in a second carburetor cast housing structure generally designated by numeral 59. The casting 59 is secured to the upper casting 22 previously described.

The pair of valves 60 and 62, which are secured to a primary throttle shaft 68, comprise the primary throttle valves and the remaining valves 64 and 66, which are secured to a secondary throttle shaft 70, comprise the secondary throttle valves. A suitable linkage element 72, which forms a part of the throttle linkage mechanism, is positively connected to the primary throttle valve shaft 68 in a suitable manner.

Referring next to the side view of Figure 4, the linkage element 72 and the associated linkage elements are shown in more particular detail. The element 22 has formed thereon suitable eyelets 74 which are adapted to receive portions of a suitable manually actuated throttle linkage mechanism. The element 72 is also linked to a lever 76 by means of linkage element 78 thereby causing the shaft 38, upon which lever 76 is secured, to move in response to primary throttle movement. The movement of shaft 38 is effective to control the metering jets and the accelerator pumping mechanism housed within casting portion 36.

Link elements 80 and 82 operatively connect the choke valve shaft 28 with another link element 84 which is rotatably mounted upon a portion of the casting portion 59. A lost motion connection is provided at 86 between the element 84 and another element 88 which is mounted concentrically with respect to element 84 and which is also rotatable about the common axis.

An abutment element is provided at 90 on the primary throttle linkage element 72 and is adapted to contact the element 88 when the primary throttle shaft 68 and the integral element 72 are rotated to a position which is close to the full throttle position. Upon further movement of the element 72 toward the full or wide open throttle position, the element 88 will be caused to rotate which in turn causes the element 84 to rotate in the same direction by virtue of the lost motion connection 86. If at this time the choke valve 32 is closed, the movement of element 84 will cause the links 82 and 80

to move the choke valve to a partially open position. If the choke valve has been opened by the thermostatic device 24, the slack in the lost motion connection 86 is increased and therefore any movement of element 88 by element 72 will have no effect upon the position of element 84.

The element 88 is also provided with a cam surface 92 which is adapted to be contacted by an adjustable stop device 94 carried by the element 72. When the choke valve 32 is in the closed position, the cam 92 and stop 94 prevent the primary throttle from fully closing. Also, if the primary throttle is fully closed when the choke valve 32 is open, the cam 92 and stop 94 are effective to prevent the choke valve from subsequently moving to the fully closed position.

Referring next to the side view of Figure 2, it is seen that a bracket 96 is secured by means of screws 98 to a flange portion 100 of the upper casting portion 22. The bracket 96 has a main portion thereof disposed in a substantially vertical plane alongside the lower casting portion 59.

The end portion of bracket 96 is bent at a right angle to the main portion 96 and is shown at 100. A pressure responsive actuator device 102, which is shown partly in cross section in Figure 2, is secured to the end bracket portion 100 by means of a suitable threaded adaptor and nut 104.

The device 102 includes a housing 106 which may include one or more flexible diaphragms 108 which extend transversely across the interior of the casting 106. The peripheral portion of the diaphragm 108 may be secured between the axial ends of the housing 106 and suitable end caps 110 and 112. If a double diaphragm actuator is used, as in the disclosed embodiment, a suitable partition wall 114 may be provided to separate the diaphragms into a pair of working chambers.

An actuator shaft 116 may be slidably received within the end cap 110 and the partition wall 108 and secured to the central portion of each diaphragm 108. The shaft 116 extends transversely through the bracket portion 100 and the adaptor and nut 104 in parallel relationship with respect to the bracket portion 96. The end of shaft 116 carries a shoulder member 118 which may be slidably disposed around the shaft 116 adjacent a nut 120 which is threadably carried by the end of shaft 116.

A spring 119 surrounds shafts 116 and is interposed between the shoulder 118 and the nut 104 thereby urging the shaft 116 in an outward direction away from the device 102.

A link element 122 is adapted to interconnect the end of shaft 116 and one arm of a bell crank 124 which is pivotally mounted to the bracket portion 96. The other arm of the bell crank 124 is linked to a control element 126 by means of the link element 128.

An abutment portion 130 is carried by the element 126 at one side of the connection between elements 128 and 126. A control element 132 is rotatably connected to the element 126 at 134 on the other side of the above-mentioned connection between elements 128 and 126. The control element 132 is fixed to one end of the secondary throttle shaft 70 which extends through the side of the lower casting portion 59.

The primary throttle shaft 68, which also extends through the side of the casting portion 59, carries an arm 136 which carries an abutment member 138 at one end thereof. The member 138 is pivoted to the end of arm 136 upon a suitable fastener 140 and is urged toward a fixed position relative to the arm 136 by means of an offset spring means 142.

A stop 144 may be formed on the lower casting portion 59 to contact a mating shoulder 146 formed on the element 132 when the secondary throttle reaches the fully closed position. A suitable spring means may be provided for resiliently urging the shoulder 146 against the stop 144 to keep the secondary throttle closed when it

is not functioning to regulate the auxiliary stage of the carburetor. A portion of such a spring means may be seen in Figure 2 at 148.

The pressure responsive actuator device 102 may be provided with suitable conduits 150 and 152 which may be connected to the discharge side and the intake side, respectively, of the coolant pump for the internal combustion engine with which the present carburetor is adapted to be used. A quick action control valve, which will subsequently be described with reference to the other embodiments of the present invention, may be interposed in the fluid conduits interconnecting the device 102 and the engine coolant pump.

The operation of the embodiment of Figures 1 through 4 may best be described with reference to the perspective views of the throttle valve control elements shown in Figures 5, 6, and 7. During low speed operation of the engine, the engine coolant pump pressure, which is proportional to engine speed, acts against one of the diaphragms 108 through the conduit 150 but the force exerted upon the diaphragm 108 by the coolant pressure is insufficient at the lower engine speed ranges to overcome the force exerted by spring 119. Thus the shaft 116 remains stationary in the position shown in Figure 5.

Upon movement of the primary throttle toward the open position through a manually actuated throttle linkage, the arm 136 is adapted to rotate with the primary throttle shaft from the position shown in Figure 2 to that shown in Figure 5. When the wide open position is reached for the primary throttle, the arm and the member 138 assume the position shown in Figure 5 which shows the member 138 in close proximity to the abutment portion 130. The secondary throttle valves are maintained in a closed position throughout this low speed operation.

During operation of the engine throughout a higher speed range, the engine coolant pressure may increase to a sufficiently high value to cause the diaphragms 108 to move the shaft 116 axially against the force exerted by the spring 119. This movement of the shaft 116 causes the bell crank to rotate about its pivot point thus causing the element 126 to rotate about the connection 134 to an upward position as shown in Figure 6.

When the primary throttle valves are moved toward the wide open position during this high speed engine operation the member 138 will contact the abutment 130 before the fully open primary throttle position is reached. Upon further movement of the primary throttle toward the wide open position the arm 136 and member 138 will then cause the element 176 to rotate about its pivotal connection with the link 128 thus causing the connection 134 at the other end of element 126 to move in an upward direction. This upward movement causes the secondary throttle valve to open by virtue of the connecting element 132.

The valves and valve control elements, as seen in Figure 6, are shown in the positions each assumes at the instant that the member 138 contacts the abutment 130. The shaft 116 is shown in the operative position it assumes when the pressure responsive device 102 is energized. The spring 119 is shown in the compressed position and the element 126 is rotated about the connection 134 which causes the fulcrum point for the element, namely, the connection with link 128, to be shifted in an upward direction.

Upon continued movement of the primary throttle to the full throttle position while the device 102 is thus energized, the valves and control levers each assume the position shown in Figure 7. The arm 136 and member 138 cause the element 126 to rotate about its connection with link 128 which causes the secondary valves 60 and 62 to open.

Referring next to Figures 8 and 9, a modified linkage arrangement is illustrated schematically. The primary throttle barrel is shown at 202 and the secondary barrel

is shown at 204. A primary valve 206 is rotatably disposed within the primary barrel 202 and a secondary valve 208 is similarly disposed in barrel 204. The primary throttle valve 206 may be actuated by means of a suitable linkage such as that shown at 210, 212, 214, 216, and 218. The component 218 of the linkage may be manually actuated in the usual manner.

The linkage component 210 is linked to a lever 220 by element 222 which is joined to lever 220 at a substantially central position. The lever 220 is connected at 224 at one end thereof to shaft 116 of the device 102 previously described in connection with the embodiment of Figures 1 through 7. The free end 226 of the lever 220 is adapted to swing in an arc which is included by the angle θ .

The secondary throttle valve 208 is secured to a linkage element 228 which is biased in a valve closing direction by a spring 230. A projection 229 is fixed to the element 228 in the path of movement of the end 226 of lever 220.

The engine coolant pump is shown schematically at 232 and a high pressure pump discharge conduit is shown at 234. The conduit 234 extends to a quick action control valve 236 which comprises a two-part housing 238 having an interior cavity 240 within which a ball 242 is adapted to freely move. The ball 242 may be formed of steel or any other suitable material.

Another fluid conduit 244 is connected to one end of the valve housing 238 and extends to the end cap 112 of the device 102 thus establishing fluid communication between the valve interior 240 and a working chamber within one portion of the device 102. A branch conduit 246 is effective to establish communication between conduit 244 and the low pressure intake side of the pump 232.

The conduits 234 and 244 are connected to the valve housing 238 at opposite ends thereof in coaxial alignment. Another conduit 248 is connected with the housing 238 at a point intermediate the connections with conduits 234 and 244. Conduit 248 extends to the end cap 110 of the device 112 thus establishing fluid communication between the interior 240 of valve housing 238 and another working chamber within another portion of the device 102.

The operation of the embodiment of Figures 8 and 9 is substantially as follows. The primary throttle valve is controlled and actuated in the usual manner through linkage 210, 212, 214, 216, and 218. Movement of the primary throttle valve 206 is accompanied by movement of the linkage component 210 which in turn causes the lever 220 to oscillate about the connection 224. The resulting movement of the free end 226 of lever 220 is insufficient to cause contact between the same and the projection 229 on element 228.

As the engine speed increases, the flow through the valve 236 and the coolant 234, 244 and 246 is also increased. At a predetermined engine speed the flow rate is of a sufficient magnitude to cause the ball 242 to be raised within the interior 240 thereby blocking off the connection with conduit 244. At this instant the pressure in the valve interior 238 and line 248 will build up and is in turn communicated to the device 102. This pressure acts upon one of the diaphragms 108 thus causing the actuator shaft 116 to shift toward the device 102 against the force exerted by spring 119.

The lever 220 assumes the position shown in Figure 9 at the instant the device 102 is energized. The end 226 is thereupon brought into close proximity to the projection 229 on element 228. Upon movement of the primary throttle valve to a predetermined position after the device 102 is energized, the lost motion gap between the projection 229 and the end 226 is closed. Upon further movement of the primary throttle toward the inside open position the secondary throttle valves 208 are opened.

Referring next to the embodiment of Figure 10, a modi-

fied linkage arrangement is shown. The primary barrel is shown at 302 and the secondary barrel is shown at 304. A primary throttle valve is shown at 306 pivotally mounted within barrel 302 and a secondary throttle valve is shown at 308 pivotally mounted within barrel 304. A lever 310 is secured to the primary throttle valve and is manually actuated by means of the usual throttle linkage.

A lever 320 interconnects one end of the actuator shaft 116 of the pressure responsive device 102 and one end of link 322. The other end of link 322 is joined to the lever 310.

The secondary throttle valve 308 is secured to an element 328 which has a projecting portion 376 at one end thereof. An element 324 is rotatably mounted upon the secondary throttle valve shaft at one end thereof and the other end is connected to the central portion of lever 320 by link element 332. The secondary throttle valve is biased toward the closed position by a spring 330.

In the operation of the embodiment of Figure 10, the movement of the primary throttle valve causes the lever 320 to oscillate about its connection with shaft 116 which causes the element 324 to oscillate about the secondary throttle shaft by virtue of the connection between lever 220 and element 324.

When the engine is operating below a predetermined speed the position of the shaft 116 is as shown in Figure 10. Under these conditions the oscillatory movement of element 324 is insufficient to cause contact between the same and the projecting portion 376 on element 328. However, when the device is actuated in the manner previously explained the shaft 116 is shifted so as to move the element 324 into closer proximity to the projecting portion 376. Upon subsequent movement of the primary throttle beyond a predetermined setting the element 324 will then contact portion 376 and cause the secondary throttle valve 308 to open.

Referring next to Figure 11, another embodiment is shown wherein the pressure responsive device 102, previously described, is utilized to directly actuate the secondary throttle valve. As seen in the figure, the actuator shaft 116 of the device 102 is directly connected to an element 402 which in turn is fixed to the secondary throttle shaft. Movement of the shaft 116 will therefore cause the secondary throttle valve, shown at 424, to oscillate within the secondary barrel, shown at 406.

The primary barrel is shown at 408 and has mounted thereon a primary throttle valve 410. A cam element 412 is secured to the primary throttle shaft at one end thereof in a convenient location. A suitable manually actuated throttle linkage is provided at 414, 416, and 418 and is operatively connected to the primary throttle in the usual manner to actuate the same.

A cam follower 420 is suitably mounted upon an actuator rod 422 which may be slidably disposed within any convenient structure either on the carburetor casting itself or at a location remote thereto as desired. The rod and cam follower are biased toward the cam 412 so that the cam follower is maintained in contact with the cam 412 at all time. The rod 422 extends within a valve housing 424 through a suitable tubular structure 426 joined to the housing 424.

The housing 424 is similar to the valve housing previously described in connection with the previous embodiments and has disposed thereon a ball valve element designated by numeral 428.

The discharge side of the engine coolant pump 232 is tapped by means of a conduit 430 which delivers fluid to the interior of housing 424 at a point directly opposite the tubular structure 426. Another conduit 431 extends from the interior of housing 424 to the pressure responsive device 102 at one side of the partition 114. Another conduit 432 interconnects the space surrounding rod 422 with the device 102 at the other side of the partition 114. A bypass conduit 434 connects the conduit 432 with the intake side of pump 232.

In the operation of the embodiment of Figure 11, the primary throttle valve is actuated in the usual manner by means of the manually actuated linkage 414, 416 and 418. When the throttle valve 410 is in the closed position, as shown in Figure 11, the cam follower 420 causes the rod 422 to be depressed into the housing 424 thus preventing the ball 428 from rising to the upper portion of the interior of the valve and from blocking off the opening into the tubular structure 426.

When the primary throttle valve is moved to a predetermined setting, the rod 422 is moved upwards a sufficiently great distance to permit the ball 428 to block off the opening at the connection with the tubular structure 426.

During operation of the engine below a predetermined speed, the ball will assume the position shown in Figure 11 and the secondary throttle will be maintained closed throughout the operating range of the primary throttle 410 by virtue of the force exerted by spring 119 on shaft 116.

During operation of the engine above a predetermined speed and at a primary throttle opening in excess of a predetermined setting, the ball 428 will be moved by the liquid coolant passing through the valve housing 424 thereby causing the passage through the tubular structure 426 and conduit 432 to be blocked. Thereupon a pressure build-up will occur in conduit 431 and one working chamber in the device 102 thereby causing the shaft 116 to be moved against the force of spring 119 to actuate the secondary throttle.

If the primary throttle 410 is thereafter moved toward a closed position during high speed engine operation, the rod 422 will be depressed by the cam 412 thereby shifting the ball 428 and opening the tubular structure 426 and conduit 432 to the high pressure discharge side of pump 232. High pressure coolant will therefore be admitted to both working chambers of the device 102 and the forces exerted upon each of the diaphragms 108 will oppose and cancel each other. The spring 119 will thereupon be effective to close the secondary throttle valve 404. Thus, the secondary throttle may be opened only when the engine speeds are above a predetermined value and when the primary throttle valve is simultaneously opened to a position above a predetermined setting.

Figure 12 shows another modification of the invention which employs a different type of quick action control valve. The valve consists of a housing 502 which includes two opposed portions 504 and 506 which are joined together at mating peripheral flanges 508. A flexible diaphragm 510 extends transversely across the interior of the housing and is secured between the peripheral flanges 508. The central portion of the diaphragm has secured thereto a pair of valve elements 512 and 514 which extend perpendicularly to the plane of the diaphragm. A spring 516 is interposed between the housing portion 506 and the diaphragm 510 and urges the diaphragm axially in one direction.

A fluid conduit 518 interconnects the high pressure discharge side of engine-coolant pump 232 and a working chamber on one side of the diaphragm 510. This chamber is designated in Figure 12 by the symbol X. Another conduit 520 extends from the working chamber on the other side of the diaphragm 510 to the low pressure intake side of the pump 232. This second working chamber is designated by the symbol Y.

Valve ports are provided at 522 and 524 substantially in the center of the housing portions 504 and 506, respectively, and are each connected to a common conduit 526. The valve elements 512 and 514, carried by the diaphragm 510, extend into close proximity to the ports 522 and 524, respectively. The conduit 526 is connected at its extreme end to a pressure responsive actuating device 528. A bypass conduit 527 interconnects the conduit 526 and the valve port 524 in the housing portion 506.

The device 528 consists of a pair of opposed housing portions 530 and 532 which define an interior cavity within which a flexible diaphragm 534 is transversely disposed.

Diaphragm 534 may be secured about its periphery between the mating peripheral edges of the housing portions 530 and 532.

A primary throttle barrel is shown at 536 and a secondary throttle barrel is shown at 538. Throttle valves 540 and 542 are rotatably mounted within the primary and secondary barrels respectively. Primary throttle valve 540 may be actuated by a manually actuated throttle linkage in the usual manner. The secondary throttle valve 542 is operatively connected to the center on diaphragm 534 by means of linkage elements 544 and 546. A spring 548 may be interposed between the housing portion 532 and diaphragm 534 to bias the secondary throttle valve into a normally closed position.

In the operation of the embodiment of Figure 12, engine coolant may be tapped from the discharge of the pump 232 and conducted into the working chamber X through conduit 518. During operation of the engine below a predetermined speed any coolant which may pass around the valve element 512 into the port 522 will be directed through the conduit 527 back into the port 524 and then into the intake side of the coolant pump through conduit 520. Upon an increase in the engine speed beyond this predetermined limiting speed, the pressure differential 25 across the coolant pump 232, which is also applied across the diaphragm 510, will cause the diaphragm 510 to shift to the right, as viewed in Figure 12, thus causing the port 524 to become restricted while simultaneously opening the port 522. This shifting motion will cause a pressure build-up to occur in conduit 526 which is transmitted to one side of the diaphragm 534 thus causing the same to shift against the force exerted by spring 548 to open the secondary valve 542. Upon a subsequent decrease 30 in the engine speed to a value below the predetermined limit, the differential pressure across the diaphragm 510 will be insufficient to maintain the diaphragm 510 and the valve elements 512 and 514 in a shifted position and the spring 516 will be effective to return the valve elements to the neutral position, as shown in Figure 12.

Figure 13 shows a modified quick action control valve which may be substituted for the valve of the embodiment of Figure 12. This modified valve comprises a housing 602 which also has two opposed portions 604 and 606 joined at mating peripheral flanges 608. A flexible diaphragm 610 extends across the interior of the housing 602 and carries at its center a pair of flat valve elements 612 and 614. The fluid conduits which provide communication between the pump 232 and a secondary throttle valve actuating device may be arranged in a manner similar to that of Figure 12. The conduits 618 and 620 correspond in function to conduits 518 and 520 in Figure 12, respectively.

Valve ports are provided in the housing portions 604 and 606 at 622 and 624 respectively. A spring 638 is interposed between the diaphragm 610 and the housing portion 606 and is effective to bias the diaphragm 610 and one valve element coaxially against an inwardly directed extension 636 of the conduit 626.

A conduit 626 is connected to the valve port 622 and extends to one side of a flexible diaphragm within a pressure responsive actuator, not specifically illustrated. The other side of the flexible diaphragm of the pressure responsive actuator is connected to the low pressure conduit 620 by means of conduit 634. Such a pressure actuator may include a housing and the flexible diaphragm therein may divide the interior of the housing into a pair of working chambers, each of which are connected to conduits 626 or 634 respectively.

The other side of the flexible diaphragm 610 may be connected to conduit 620 by means of conduit 629. A bypass conduit is provided at 627 which interconnects conduit 626 with port 624.

In the operation of the modified valve of Figure 13, the pressure differential which exists across the pump 232 is impressed upon opposite sides of diaphragm 610 through the conduits 618 and 620. During the operation

of the engine below a predetermined limiting value, the position of the diaphragm 610 and the valve elements 612 and 614 are shown in Figure 13. Upon a subsequent increase in the engine speed, the coolant pump pressure becomes sufficiently great to deflect the diaphragm 610 and its associated valve elements against the force exerted by spring 638 to close the valve port 624 while simultaneously opening port 622. The fluid pressure will thereupon increase in the conduit 626, and one side of the flexible diaphragm in the pressure responsive actuator device. At the same time, the other side of the flexible diaphragm in the actuator device is connected to the intake side of the engine coolant pump. The actuator device is therefore responsive to coolant pressure differential across the pump.

Upon being energized, the actuator device will open the secondary throttle valve to which it may be linked in the usual manner. Upon a subsequent decrease in pump pressure differential, the spring 638 will urge the valve element 612 against port 622 thus decreasing the pressure acting against the diaphragm of the actuator device.

In all of the preceding embodiments herein disclosed, the actuating device for the secondary stage is responsive only to the pressure differential across the engine coolant pump. Therefore the absolute value of the pump discharge pressure may be subject to variation without affecting the calibration of the carburetor control mechanism.

While certain preferred embodiments of the invention have been specifically disclosed, it is understood that the invention is not limited thereto as many variations will be readily apparent to those skilled in the art, and the invention is to be given its broadest variation within the terms of the following claims.

I claim:

1. In a liquid coolant internal combustion engine having an intake manifold and a liquid coolant pump, at least two conduits for supplying a combustible mixture to said intake manifold, a throttle valve in each of said conduits, means for actuating one of said valves for controlling the passage of a portion of said combustible mixture to said manifold, other means for actuating a second valve in another of said conduits to supply an additional controlled charge of combustible mixture to said manifold during the operation of said engine within a predetermined speed range, said other means including portions mechanically controlled by said first named means, and means responsive to variation in engine coolant pump pressure for moving one of said controlled portions to an inoperative position when the engine coolant pressure exceeds a predetermined value during the operation of said engine within another predetermined range of engine speeds.

2. In a multiple stage carburetor for a liquid cooled internal combustion engine having an engine driven coolant pump, a plurality of induction passages, throttle valves in each of said passages, means for controlling the operating position of said valves including a portion connected to one of said valves and another portion connected to another of said valves, said means further including a one way mechanical connection between said portions which provides for simultaneous movement of both of said valves during movement of said one valve within a predetermined range of operating positions, and means responsive to variations in engine coolant pump pressure for adjusting the relative position of said portions to render the same ineffective to control the position of said other valve at engine speeds below a predetermined limiting value.

3. In a liquid cooled internal combustion engine having an engine coolant pump and an intake manifold, at least two conduits for supplying a combustible mixture to said intake manifold, a throttle valve in each of said conduits, means for actuating one of said valves for controlling the passage of a portion of said combustible mix-

ture to said manifold, other means for actuating a second valve in another of said conduits to supply an additional controlled charge of combustible mixture to said manifold during the operation of said engine within a predetermined speed range, said other means including portions mechanically controlled by said first named means, and means responsive to engine coolant pump pressure for moving said controlled portions to an inoperative position during the operation of said engine within another predetermined range of engine speeds.

4. In a liquid cooled internal combustion engine having an engine coolant pump and an intake manifold, at least two conduits for supplying a combustible mixture to said intake manifold, a throttle valve in each of said conduits, a first linkage element operatively connected to one of said valves, a second linkage element connected to the other of said throttle valves, means for moving said second linkage element into and out of an operative position in response to pressure differential across said engine coolant pump, said elements being adapted to engage each other upon movement of said one throttle valve beyond a predetermined setting when said second linkage element is in an operative position to actuate the other of said throttle valves and to control the supply of combustible mixture to said manifold.

5. In a multiple stage carburetor for a liquid cooled internal combustion engine having an engine driven coolant pump, a plurality of induction passages, throttle valves disposed within each of said passages, linkage means for actuating one of said valves, means for actuating the other of said valves having a portion thereof adapted for engagement with a portion of said linkage means during movement of the latter within a predetermined range of operating positions, and means for adjusting the relative positions of said portion of said second named means with respect to said linkage means in response to variations in coolant pressure differential across said pump.

6. In a multiple stage carburetor for a liquid cooled internal combustion engine having an engine driven coolant pump, a plurality of induction passages, throttle valves in each of said passages, means for controlling the operating position of said valves including a portion connected to one of said valves and another portion connected to another of said valves, said means further including a one way mechanical connection between said portions which provides for simultaneous movement of both of said valves during movement of said one valve within a predetermined range of operating positions, and means responsive to pressure differential variations across said engine coolant pump for adjusting the relative position of said portions to render the same ineffective to control the position of said other valve at engine speeds below a predetermined limiting value.

7. In a multiple stage carburetor for use with a liquid cooled internal combustion engine, a primary induction passage, a secondary induction passage, primary and secondary valves mounted within said primary and secondary passages respectively, means for controlling the position of said primary throttle valve, a control element operatively fixed to said secondary valves, a one way mechanical connection between said element and said control means for actuating the secondary valve during movement of said primary throttle valve within a predetermined range of operating positions, and means responsive to pressure variations between the discharge and intake sides of said engine coolant pump for rendering said secondary valve inoperative during operation of said engine within another predetermined range of engine speeds.

8. In a two stage carburetor for an internal combustion engine, a plurality of induction passages, a primary valve in one of said passages, a secondary valve in another of said passages, a first link element fixed to said primary valve and movable therewith during manual

operation of said primary valve, a second link member fixed to said secondary valve, a third link member pivotally connected near one end thereof to said second member and operatively connected to a movable fulcrum member at a central portion thereof, said first member being adapted to engage and actuate said second member near the other end thereof during movement of the primary throttle through a predetermined range of engine speeds, and means responsive to engine speed for adjusting the position of said fulcrum member to render the secondary valve inoperative during operation of the engine within another predetermined range of engine speeds.

9. A two stage carburetor as set forth in claim 8 wherein said engine is liquid cooled and wherein said engine speed responsive means includes an actuator device having a movable actuator shaft, conduit means for conducting engine coolant to said device thereby providing an engine speed signal for energizing the same, and linkage means connecting said fulcrum member to said actuator shaft.

10. In a two stage carburetor for a liquid cooled internal combustion engine having an engine driven coolant pump, a plurality of induction passages, throttle valves disposed within each of said passages, linkage means for manually actuating one throttle valve in one of said passages, a one way mechanical connection between said one throttle valve and another throttle valve in another of said passages for actuating said other throttle valve throughout a predetermined range of operating positions for said one throttle valve, said connection including cooperating linkage elements connected to said primary and secondary valves respectively, and means responsive to engine coolant pump pressure differential across said coolant pump for shifting one of said linkage elements to a relatively remote position with respect to said other linkage element to render said connection inoperative at engine speeds below a predetermined limiting value.

11. In a two stage carburetor for a liquid cooled internal combustion engine having an engine driven coolant pump, a plurality of induction passages, throttle valves disposed within each of said passages, linkage means for manually actuating one throttle valve in one of said passages, a one way mechanical connection between said one throttle valve and another throttle valve in another of said passages for actuating said other throttle valve throughout a predetermined range of operating positions for said one throttle valve, said connection including cooperating linkage elements connected to said primary and secondary valves respectively, means responsive to engine coolant pump pressure differential across said coolant pump for shifting one of said linkage elements to a relatively remote position with respect to said other linkage element to render said connection inoperative at engine speeds below a predetermined limiting value, said pressure responsive means including an actuator device, a movable actuator shaft operatively carried by said device, a mechanical connection between said actuator shaft and said one linkage element to shift the same, and conduit structure interconnecting said device with said coolant pump.

12. In a two stage carburetor for a liquid cooled internal combustion engine having an engine driven coolant pump, a plurality of induction passages, throttle valves disposed within each of said passages, linkage means for manually actuating one throttle valve in one of said passages, a one way mechanical connection between said one throttle valve and another throttle valve in another of said passages for actuating said other throttle valve throughout a predetermined range of operating positions for said one throttle valve, said connection including cooperating linkage elements connected to said primary and secondary valves respectively, means responsive to engine coolant pump pressure differential

across said coolant pump for shifting one of said linkage elements to a relatively remote position with respect to said other linkage element to render said connection inoperative at engine speeds below a predetermined limiting value, said pressure responsive means including an actuator device, a movable actuator shaft operatively carried by said device, a mechanical connection between said actuator shaft and said one linkage element to shift the same, and conduit structure interconnecting said device with said coolant pump, said conduit structure including a quick action control valve interposed therein for controlling the transfer of engine coolant pump pressure to said device.

13. In a multiple stage carburetor for use with liquid cooled internal combustion engines having an intake manifold and an engine driven coolant pump, a plurality of passages for supplying a combustible mixture to said manifold, a primary throttle valve in one of said passages, a secondary throttle valve in another of said passages, means for manually controlling said primary throttle valve, a mechanical lost motion connection between said valves including linkage portions having a lost motion gap therebetween, a pressure responsive actuating device, an actuator rod forming a portion of said device and connected to another portion of said lost motion connection, and conduit means for connecting said device to said engine coolant pump to provide said device with coolant pump pressure, said actuator device being adapted to move said other portion upon being energized with engine coolant pressure thereby reducing the magnitude of said lost motion gap.

14. A multiple stage carburetor as set forth in claim 13 wherein said actuator device includes a housing and a pair of opposed working chambers in said housing, and wherein said conduit means includes a fluid control valve housing, a spherical valve element disposed within said housing, a pair of valve ports in said housing and axially aligned with respect thereto, a third valve port located intermediate said pair, a first conduit interconnecting one of said pair of ports with the discharge side of said pump, a second conduit connecting the other of said pair of ports with the intake side of said pump, a third conduit connecting said second conduit to one of said pairs of working chambers, and a fourth conduit connecting said intermediate valve port to the other of said working chambers, said spherical valve element being adapted to block the other of said pair of valve ports when a predetermined pressure differential is reached across said pump thereby causing an actuating pressure differential to build-up in said working chambers to shift said actuator rod.

15. In a multiple stage carburetor for use with a liquid cooled internal combustion engine having an intake manifold and an engine driven coolant pump, a plurality of passages for supplying a combustible mixture to said manifold, a first throttle valve in one of said passages, a second throttle valve in another of said passages, a linkage for manually actuating said first throttle valve, an engine coolant pressure responsive device including a movable actuating member, conduit means for supplying engine coolant pump pressure to said device to actuate the same, a lost motion element fixed to said second throttle valve, another cooperating lost motion element rotatably mounted upon a portion of said second throttle valve, a first link element operatively connected to said actuator shaft at one end thereof, said first throttle being mechanically connected to the other end of said link element, and another link connection between the intermediate portion of said first link element and said other lost motion element.

16. In combination with a multiple stage carburetor for a liquid cooled internal combustion engine having an engine coolant pump, at least one pair of induction passages, a primary throttle valve in one of said passages, a secondary throttle valve in another of said passages;

a pressure responsive actuator device having a movable portion thereof operatively connected to said secondary throttle to actuate the same, a pair of opposed working chambers within said actuator device, fluid conduit structure for delivering coolant pressure from said pump to said working chamber, a quick action control valve interposed in said conduit structure for causing said actuator device to be energized when the coolant pressure exceeds a predetermined minimum value, and means for rendering said control valve inoperative when the primary throttle is operated within a predetermined range of positions.

17. The combination as set forth in claim 16 wherein said control valve comprises a housing, a spherical valve element adjustably disposed within said housing, a pair of opposed valve ports in said housing on diametrically opposite sides of said valve element, an intermediate valve port in said housing, a first conduit connecting one of said pair of ports to the discharge side of said pump, a second conduit connecting the other of said pair of ports to one of said working chambers, a third conduit connecting said intermediate port with the other of said working chambers, a bypass conduit connecting said second conduit to the intake side of said pump, and wherein said means for rendering said control valve inoperative includes a rod slidably disposed within said housing and adapted to control the movement of said valve element, and means for moving said rod into contact with said valve element in response to movement of said primary throttle valve, said rod thereby preventing movement of said valve element.

18. In combination with a multiple stage carburetor for use with a liquid cooled internal combustion engine, at least two induction passages, a primary throttle in one of said passages, a secondary throttle valve in another of said passages, a pressure responsive actuator device having a movable actuator shaft thereof operatively connected to said secondary throttle valve, said actuator device including at least one movable wall element partly defining opposed working chambers, said actuator shaft being connected to said movable element, a quick action control valve, said control valve including a flexible diaphragm partly defining opposed pressure chambers on either side thereof, conduit means for connecting said pressure chambers to the intake and discharge sides of said pump, metering ports disposed on opposite sides of said diaphragm, other conduit means for connecting said ports to one of said working chamber, and movable valve elements carried by said flexible diaphragm for selectively restricting said ports in response to pressure differential variations across said pump.

19. The combination as set forth in claim 18 wherein said movable valve elements comprise projections extending at least partially through said ports for variably restricting the same.

20. The combination as set forth in claim 18 wherein said movable valve elements comprise flat valve discs adapted to selectively cover said ports to restrict the same.

21. A two stage carburetor for use with a liquid cooled internal combustion engine having a coolant pump and an intake manifold, at least two conduits for supplying a combustible mixture to said intake manifold, a throttle valve in each of said conduits, linkage means for actuating one of said throttle valves, and means for actuating another of said throttle valves in response to coolant pressure differential across said coolant pump.

22. In a multiple stage carburetor for a liquid cooled internal combustion engine having an intake manifold and an engine coolant pump, at least one pair of induction passages for supplying a combustible mixture to said manifold, throttle valves in each of said passages, linkage means for actuating a first of said throttle valves, a one way mechanical connection between said valves providing for simultaneous movement of said first and a second of said throttle valves during movement of said first throttle valve over a predetermined range of positions near the

wide open throttle setting, a pressure responsive actuator device having a pair of opposed working chambers therein, a movable actuator shaft operatively connected to said device, a portion of said one way connection being connected to said actuator shaft, conduit means for connecting said working chambers to either side of said coolant pump, and valve means for regulating the distribution of coolant pump pressure through said conduit means so as to selectively apply coolant pump discharge pressure to either one or both of said working chambers as determined by the magnitude of the engine speed.

23. A two stage carburetor for use with a liquid cooled internal combustion engine having a coolant pump and an intake manifold, at least two conduits for supplying a combustible mixture to said intake manifold, a throttle valve in each of said conduits, linkage means for actuating one of said throttle valves, and means for actuating another of said throttle valves in response to coolant pressure differential across said pump, said last named means including a pressure responsive actuating device, a fluid passage interconnecting said device with each side of said coolant pump, and a quick action flow control valve interposed in said passage for regulating the distribution of engine coolant pressure in said passage whereby said coolant pressure may be applied to said device to actuate the same only at engine speeds above a predetermined limiting value.

24. A two stage carburetor as set forth in claim 23 wherein said quick action control valve includes a valve housing, a flexible diaphragm within said housing, valve ports in the wall of said housing on either side of said diaphragm, and valve elements carried by said housing for restricting said ports, said passage including portions connecting opposite sides of said diaphragm to respectively opposite sides of said pump and other portions connecting at least one of said ports to said actuating device.

25. A two stage carburetor as set forth in claim 23 wherein said quick action control valve includes a hollow valve housing, a plurality of valve ports in said housing, and a spherical valve element disposed within said housing between two of said ports for alternately restricting the same, said passage including portions connecting certain of said ports to respectively opposite sides of said pump and other portions connecting at least one other port to said actuator device.

26. A two stage carburetor as set forth in claim 23 wherein said linkage means include portions comprising a lost motion mechanical connection between said throttle valves.

27. A multiple stage carburetor for a liquid cooled internal combustion engine having an engine driven coolant pump and an intake manifold, said carburetor comprising a primary throttle stage and at least one auxiliary throttle stage, said stages each including means for supplying a combustible mixture to said engine manifold, and means for controlling the operation of said auxiliary stage in response to coolant pressure differential across said pump.

28. In an internal combustion engine having an intake manifold, a primary mixture conduit and a secondary mixture conduit for supplying said manifold with a combustible mixture of fuel and air, a primary throttle valve mounted in said primary conduit and a secondary throttle valve mounted in said secondary conduit, linkage means interconnecting said primary and secondary throttle valves, said linkage means including a first linkage element joined to and movable with said primary throttle valve, a second linkage element joined to and movable with said secondary throttle valve, a third linkage element joined at one end thereof to said second linkage element, means for pivoting said third linkage element about a point thereon intermediate its ends, and engine speed responsive means for shifting said pivoting means to either of two operating positions, said first linkage element being adapted to contact and rotate said third

linkage element about said intermediate point when said pivoting means assumes one of said operating positions as the primary valve is moved within a predetermined range of throttle settings near the wide open position thereby opening said secondary throttle valve, said secondary throttle valve remaining in a closed position during movement of said primary throttle valve when said pivoting means assumes the other of said operating positions.

29. The combination as set forth in claim 28 wherein said engine speed responsive means comprises a pressure responsive actuator having portions operatively connected to said linkage means, said engine being provided with an engine driven engine coolant pump, and conduit means providing communication between said pump and said pressure responsive actuator, said pressure responsive actuator being energized by engine coolant pressure when the engine speed exceeds a predetermined maximum value.

30. In an internal combustion engine having an intake manifold, a primary mixture conduit and a secondary mixture conduit for supplying said manifold with a combustible mixture of fuel and air, a primary throttle valve mounted in said primary conduit and a secondary throttle valve mounted in said secondary conduit, linkage means interconnecting said primary and secondary throttle valves, said linkage means including a first linkage element joined to and movable with said primary valve, a second linkage element joined to and movable with said secondary valve, an engine responsive actuator including a movable actuator shaft, a third linkage element pivoted at one end thereof to said actuator shaft, an intermediate portion of said third linkage element being joined to said first linkage element, said actuator shaft being adapted to assume either of two operative positions, the other end of said third linkage element being adapted to contact and to rotate said second linkage element and to open said secondary throttle valve when said actuator shaft assumes one operating position as the primary throttle valve is moved within a predetermined range of operating positions near the wide open setting.

31. The combination as set forth in claim 30, wherein said engine includes an engine driven coolant pump and wherein said actuator includes a pressure responsive servo mechanism, and conduit structure providing communication between said engine coolant pump and said servo mechanism, said servo mechanism being energized upon an increase in engine conduit pump pressure beyond a predetermined value thereby shifting said actuator rod to said one operating position.

32. In an internal combustion engine having an intake manifold, a primary mixture conduit and a secondary mixture conduit for supplying said manifold with a combustible mixture of fuel and air, a primary throttle valve mounted in said primary conduit and a secondary throttle valve mounted in said secondary conduit, linkage means interconnecting said primary and secondary throttle valves, said linkage means including a first linkage element joined to and movable with said primary valve, a second linkage element joined to and movable with said secondary throttle valve, an engine speed responsive actuator including a movable actuator shaft, a third linkage element pivoted at one end thereof to said actuator shaft, a fourth linkage element pivoted at one end thereof adjacent said second linkage element, the other end of said fourth linkage element being joined to said third linkage element intermediate the ends thereof, the other end of said third linkage element being joined to said first linkage element, said second and said fourth linkage element forming a one-way connection, said actuator shaft being adapted to assume either of two operative positions and to shift said fourth linkage element into and out of a position closely adjacent said second linkage element, the secondary throttle valve being opened as the primary throttle valve is moved to a range of posi-

tions greater than the wide open setting, said fourth linkage element being adapted to contact said second linkage and to open said secondary throttle valve when it assumes said position adjacent said second linkage element.

33. The combination as set forth in claim 32 wherein said engine includes an engine driven coolant pump and wherein said actuator includes a pressure responsive servo mechanism, and conduit structure providing communication between said engine coolant pump and said servo mechanism, said servo mechanism being energized upon an increase in engine coolant pump pressure beyond a predetermined value thereby shifting said actuator shaft to one of said operating positions and shifting said fourth linkage element into said position adjacent said second linkage element.

34. In a liquid cooled internal combustion engine having an intake manifold and an engine driven coolant pump, first and second mixture conduits for supplying said manifold with a controlled combustible charge, a primary throttle valve in the first of said conduits, a secondary throttle valve in the second of said conduits, linkage means for actuating the first of said valves, pressure responsive means for actuating said secondary throttle valve comprising diaphragm structure and an actuator linkage means interconnecting said diaphragm structure and said secondary throttle valve, said diaphragm structure defining in part two opposed working chambers, conduit structure interconnecting said coolant pump with at least one working chamber of said pressure responsive means, and valve means for controlling the distribution of coolant pressure to said pressure responsive means, said valve means including a flexible valve diaphragm defining two opposed valve chambers, one of said valve chambers being connected to the high pressure side of said coolant pump and the other of said valve chambers being connected to the low pressure side of said coolant pump, said one valve chamber communicating with one of said working chambers, passage means for bypassing fluid from said one valve chamber to said other valve chamber, and a valve element carried by said valve diaphragm for restricting said bypass means upon deflection of said valve diaphragm as the coolant pump pressure differential increases beyond a predetermined value thereby causing a rapid pressure buildup in said one pressure chamber.

35. The combination as set forth in claim 34 wherein said valve diaphragm carries another valve element, said other valve element being adapted to control the degree of communication of said working chamber with said one valve chamber, the degree of communication increasing upon deflection of said valve diaphragm under the influence of engine coolant pressure differential.

36. In a liquid coolant internal combustion engine having an intake manifold and an engine driven coolant pump, first and second mixture conduits for supplying said manifold with a controlled combustible charge, a primary throttle valve in the first of said conduits, a secondary throttle valve in the second of said conduits, linkage means for actuating the first of said throttle valves, pressure responsive means for actuating said secondary throttle valve comprising diaphragm structure and an actuator linkage means interconnecting said diaphragm structure and said secondary throttle valve, said diaphragm structure defining in part two opposed working chambers, conduit structure interconnecting said coolant pump with at least one working chamber of said pressure responsive means, valve means for controlling the distribution of coolant pressure to said pressure responsive means, said valve means comprising a valve chamber, said conduit structure including separate portions respectively connecting said valve chamber with the high pressure side and the low pressure side of said coolant pump, said conduit structure including another portion connecting said valve chamber with one of said working chambers, a spherical valve element disposed in said valve chamber,

and a bypass passage means communicating with said valve chamber for conducting fluid from the high pressure side to the low pressure side of said pump, said valve means being adapted to restrict said bypass passage means upon an increase in the pressure differential across said conduit pump beyond a predetermined value thereby causing a rapid pressure buildup to occur in said one working chamber.

37. The combination as set forth in claim 36 wherein the linkage means for said primary throttle valve includes portions for restricting the movement of said spherical valve element upon movement of said primary throttle valve throughout a range of positions less than a predetermined setting thereby preventing a pressure buildup from occurring in said one working chamber while said throttle position is in said predetermined range.

38. In a liquid cooled internal combustion engine hav-

ing an engine driven coolant pump and an intake manifold, a first conduit for supplying a charge of combustible mixture to said manifold, a second conduit for supplying an auxiliary charge of combustible mixture to said manifold, a throttle valve in each of said conduits, throttle linkage means for actuating the throttle for said first conduit, and means for controlling the operation of the throttle valve for said second conduit in response to variations in coolant pressure differential across said pump.
